[57] ABSTRACT

A new cultivar of Forsythia named 'Pygmy-Red' characterized by its small shrub size, its narrow foliage, and the distinct red color of its currently matured shoots.

3 Drawing Sheets

1

This invention relates to a new cultivar of Forsythia named "Pygmy-Red", which is characterized especially by its low growth habit, its narrow leaves, and the red color of current shoots at maturity.

The new variety was derived as a seedling from a vegetative line of mutants, which had been produced in turn by subjecting rooted cuttings of parent "Lynwood Gold" (a sport of *F. intermedia* "Spectabilis").

In 1968, three hundred cuttings of "Lynwood Gold" that had been potted and held in cold storage (38° F.) for six weeks and then returned to the greenhouse for two days were irradiated with 1200 rad fast neutrons. One of the plants of this group that broke dormancy formed a shoot with variegated foliage. This plant was cut back repeatedly to induce branching and eventually formed shoots that exhibited different characteristics. Each shoot was propagated by stem cuttings over 10 vegetative generations of selection and propagation. From this plant population two vegetatively selected types and three seedlings were selected. Further propagation and testing of these selections over several more years were shown to be the stable and new forsythia varieties that are the subject of this and four other co-pending plant patent applications; viz:

2

istics. The seedling showed good growth characteristics in the field, a distinct red coloration in mature current year shoots, and maroon fall color on the upper side of the leaves. Cuttings from this plant have been rooted in soil and asexually propagated, and its progeny have displayed homogeneous and stable characteristics.

Throughout this specification, color names beginning with a small letter signify that the name of the color as used in common speech are aptly descriptive. Color names beginning with a capital letter designate values based on the R.H.S. Colour Chart, published by The Royal Horticultural Society of London, England.

The accompanying drawings illustrate the new variety in color as grown in Knox County within the State of Tennessee.

FIG. 1 illustrates "Pygmy-Red" in spring bloom. The measuring stick is set on the ground and is 4 ft. long.

FIG. 2 shows lowered cut stems.

FIG. 3 is a close-up view of the flowers of FIG. 2 which also illustrates the red color of the currently matured shoots.

FIG. 4 illustrates the "Pygmy-Red" plant in May foliage.

FIG. 5 is a closer view of the foliage shown in FIG. 4.

The following characteristics distinguish "Pygmy-Red" from its parent and other Forsythia cultivars:

THE PLANT

"Pygmy-Red" has a low growth habit. The plant form is loose, but graceful, some branches bending to the ground and rooting where they touch the soil. The plant is a hardy (to Zone 6b or lower), shows good vigor but develops few seed pods. It is a flowering shrub, blooming readily when used for forcing into

Ser. No.	Name	Type
272,063	"Lemon-Screen"	vegetative selection
273,489	"Tinkle Bells"	vegetative selection
271,919	"Minikin"	seedling
271,665	"Fairy Land"	seedling
271,666	"Pygmy-Red"	seedling

Each differs greatly from the parent "Lynwood Gold" and also from one another.

"Pygmy-Red" was selected at the seedling stage because of its distinct foliage form and growth character-

flower in a greenhouse and suitable for containers. The ultimate size of "Pygmy-Red" is about 3½ to 4½ ft. in height and 5 ft. to 6 ft. wide. The size of "Pygmy-Red" makes it particularly useful for road median planting, small visual and physical landscape screens and barriers, or for mass planting in parks. The plant requires minimal pruning and has disease and insect-resistant foliage.

Its parent, "Lynwood Gold", by contrast is tall and slender—a straight upright variety with erect stems and which attains a height of 6 ft. to 7½ ft. at maturity.

FLOWER

"Pygmy-Red" flowers at an intermediate stage. The yellow flowers (Yellow 6A in color) are 1½ in. to 1½ in. diameter and generally have four, but sometimes five, petals. The corolla lobes are narrow. The pistils extend 2/25 in. to 3/25 in. above the pollen sacs of the stamen. The plant produces two flowers per node on the flowering wood, which has internodes ½ in. to 1½ in. in length.

SHOOTS

The currently matured Pygmy-Red shoots have a distinct red color (Purple Red 59 A); high anthocyanin pigmentation of the mature current shoots is also expressed in the maroon fall color of the foliage when the plant is grown with full exposure to direct sunlight. The shoots are lamellate between nodes, flexible, bending to touch the ground, which leads to self-propagation by layering.

The stems of the "Lynwood Gold" parent are green when young and brown when mature; they are a bit stiff; the pith at the nodes is lamellate, and on one year shoots, the stems between nodes are hollow.

FOLIAGE

The "Pygmy-Red" leaves are dark green in color when both young and mature. The leaves are simple, serrate and lanceolate, being acuminate at the tip and attenuate at the base, 0.3 in. to 0.4 in. wide and 2 in. to 2½ in. long on flowering wood. The leaves on vegetative shoots are somewhat larger, up to 1 in. wide and 2½ in. long. Venation is pinnate. Few, if any, lobed leaves occur on vegetative shoots, as often occurs with other Forsythia cultivars. Even on fast growing vegetative shoots, the internodes are less than 1½ in. long.

The leaves of the "Lynwood Gold" parent, on the other hand, are ovate lanceolate in shape and about 3" to 4½" long and about 1" to 1½" wide. Both young and old leaves are deep green in color.

To facilitate the comparison of the characteristics and features of "Pygmy-Red", the subject of this application, and its parent, "Lynwood Gold" and also with the four other new mutant offspring varieties of "Lynwood Gold" referred to above, there are attached hereto as Tables 1-5 comparative tabulations of the characteristics and properties of parent and its five offspring mutants that were developed from a single irradiated plant of "Lynwood Gold." Table 1 compares "Pygmy-Red" and its parent "Lynwood Gold". Table 2 compares "Pygmy-Red" and "Fairy-Land". Table 3 compares "Pygmy-Red" and "Tinkle Bells". Table 4 compares "Pygmy-Red" and "Minikin". Table 5 compares "Pygmy-Red" and "Lemon Screen".

S/N: 271,666	PYGMY RED	LYNWOOD GOLD
<u>Plant:</u>		

TABLE 1-continued

	S/N: 271,666 PYGMY RED	LYNWOOD GOLD
5 Habit	Low, loose graceful arching to ground	Tall, slender-Upright straight & erect stems
Size, height	3½-4½'	6'-7½'
Size, width	5'-6'	
Vigor	Good vigor	
Hardiness	Hardy Zone 6b (or lower)	
10 Productivity	Readily roots where branches touch ground few seed pods	Fertile
15 <u>Stems:</u>		
Color (young)	High anthocyanin	Green
Color (mature)	Purple Red (59 A)	Brown
Rigidity	Flexible lamellate between nodes	A bit stiff; pith nodes lamellate; hollow between nodes on one year shoots
20 <u>Leaves:</u>	Simple	
Type		
Color:		
(young)	Dark Green	Deep Green
(mature)	Dark Green	Deep Green
(fall)	Anthocyanin (maroon) expressed in full sun	
25 Shape	Lanceolate (few lobed leaves on vegetative shoots)	ovate lanceolate
tip	Accuminate	
base	Attenuate	
margins	Serrate	
30 <u>Size:</u>		
length	2"-2½" on flowering wood; to 2½" on vegetative wood	3-4½"
width	0.3"-0.4" on flowering wood; to 1" on vegetative wood	1-1½"
35 Venation	Pinnate	
Flower:		
Date of Flowering	Intermediate	Late
Size: width	1½-1½"	1"-1½" (medium)
40 Color:	Yellow (7A)	Brilliant Yellow (lighter than its parent Spectabilis)
<u>Corolla:</u>		
length	Narrow	Reflexed
lobes	4 - sometimes 5	Large, broad, open
45 Petals: number		Elliptic
Pistils:	Extend 2/25"-3/25" above pollen sacs of stamens	Extend well above pollen sacs (anthers) of stamens
Number per node:	2	
Insertion angle on upright stems:		
Internodes:	1"-1½" (1½" even on fast growing shoots)	Flowers almost evenly spaced on stems
50 Stress Resistance:	disease and insect	
Utility Aspects:		

TABLE 2

	S/N: 271,666 PYGMY RED	S/N 271,665 FAIRY LAND
60 <u>Plant:</u>		
Habit	Low, loose graceful arching to ground	Small overall & fine textured: Closely spaced flowers & leaves
Size, height	3½-4½'	Dense (young) foliage
Size, width	5'-6'	3'-4'
Vigor	Good vigor	5'-6'
Hardiness	Hardy Zone 6b	Good vigor for size Zone 6b (or lower)

Plant 7,583

5

TABLE 2-continued

	S/N: 271,666 PYGMY RED	S/N 271,665 FAIRY LAND
<u>Productivity</u>	(or lower) Readily roots where branches touch ground few seed pods	Few seed pods
<u>Stems:</u>		
Color (young)	High anthocyanin	Light green
Color (mature)	Purple Red (59 A)	Brownish green
Rigidity	Flexible lamellate between nodes	Very flexible lamellate between nodes
<u>Leaves:</u>		
Type	Simple	Simple
<u>Color:</u>		
(young)	Dark Green	Medium green (fairly light)
(mature)	Dark Green	Medium green (fairly light)
(fall)	Anthocyanin (maroon) expressed in full sun	Mostly faded yellow
<u>Shape</u>	Lanceolate (few lobed leaves on vegetative shoots)	Lanceolate
tip	Accuminate	Accuminate
base	Attenuate	Attenuate
margin	Serrate	On flowering wood; entire On vegetative wood: serrate top ½
<u>Size:</u>		
length	2"-2½" on flowering wood; to 2½" on vegetative wood	On flowering wood: 1½"-2½" On vegetative shoots: about 3"
width	0.3"-0.4" on flowering wood; to 1" on vegetative wood	On flowering wood: 0.2"-0.4" On vegetative shoots 0.5-0.6"
<u>Venation</u>	Pinnate	Pinnate
<u>Flower:</u>		
Date of Flowering	Intermediate	Intermediate
Size: width	1½"-1½"	¾"-1¼"
Color:	Yellow (7 A)	Yellow (6 A)
<u>Corolla:</u>		
length	Narrow	Reflexed, small
lobes	4 - sometimes 5	Generally 4-many have 5, 6, 7 and 8 on single corolla
Petals: number		Extend 3/25" to 4/25"
Pistils:	Extend 2/25"-3/25" above pollen sacs of stamens	Extend 3/25" to 4/25" above pollen sacs (anthers) of the stamen
Number per node:	2	2-4
Insertion angle on upright stems:		
Internodes:	1"-1½" (1½" even on fast growing shoots)	¾" to about 1"
Stress Resistance:	disease and insect	
Utility Aspects:		Very well suited for container culture
